UNITED STATES PATENT OFFICE

SAMUEL E. SPERRY, OF HOLLIS, NEW YORK, ASSIGNOR TO INTERTYPE CORPORATION,
OF BROOKLYN, NEW YORK, A CORPORATION OF NEW YORK

LINE CASTING MACHINE

Application filed February 14, 1930. Serial No. 428,459.

The present invention relates to improvements in line casting machines of the general class shown and described in U. S. Letters Patent No. 436,532 granted September 16, 1890 to O. Mergenthaler wherein a line of matrices and space bands are presented in front of a mold by a so called "elevator" and molten metal is injected into the mold and against the matrix line to cast a type bar or slug having printing characters along an edge thereof.

One of the primary objects of the invention is to provide novel and improved means whereby machines of the class referred to may be adapted to cast slugs having a body portion of greater thickness than the point size of the printing characters on its printing edge, with the same speed and facility with which ordinary slugs are cast in such machines, such slugs being useful for example for the production of printed matter having wider spacing than usual between the printed lines, as in legislative bills and the like, without requiring the insertion of "leads" between the slugs.

Another object is to provide means whereby relatively thick body slugs such as those formed in the well known recessed molds but bearing a line of printing characters of any point size commonly used with two-letter matrices may be produced satisfactorily and efficiently in line casting machines of the class referred to.

Another object is to provide improved means whereby slugs having an extended body portion of greater thickness and of less height than the character bearing edge may be cast in recessed molds in which the mold cap and body are in fixed relation as distinguished from a mold wherein the cap is movable to permit ejection of the slug from the mold.

A further object of the invention is to provide novel and improved casting means for machines of the class referred to for casting slugs of the kind above referred to, whereby a part of the elevator or equivalent means which carries the matrix line to casting position in front of the mold cooperates with the recessed mold cap to form a metal-tight seal.

therewith and will always insure effective closing of the front openings of the mold cavity.

In the accompanying drawings:—

Fig. 1 is a vertical sectional view through the mold and cap, the matrix positioning elevator and the adjacent cooperative parts of a line casting machine embodying the present invention.

Fig. 2 is a perspective view of the mold cap as viewed from the front, showing the bevelled or inclined surface thereon which operates with a corresponding surface on the matrix positioning elevator; and

Fig. 3 is a perspective view of a type bar or slug such as that cast in a mold of the construction shown. 65

The invention is shown in the present instance as applied to a line casting machine of the general class disclosed in the patent hereinbefore noted, 1 representing the mold wheel or disk commonly used in such machines and carrying the slug casting mold which comprises a mold body 2 and a mold cap 3, liners 4 being interposed between the mold cap and body for spacing them, 5 represents the upper portion of the so-called "first elevator" which is movable vertically on the usual vise frame 6 and carries opposed front and rear jaws 7 and 8 which form a channel between them to contain a matrix line comprising the usual matrices M and wedgelike or expandible spacers S, the ele-

vator being operative to lower the matrix line into position in front of the mold and a justification bar 9 being arranged to force the space bands S upwardly to expand and fill out the matrix line, as is well understood in this art. 10 represents the mouth-piece of a metal pot which may be of the usual construction and may operate in the usual way to inject molten metal into the mold cavity 11 to cast a type bar or slug therein. The mold wheel 1, as is usual in machines of this class, is reciprocable in a forward and rearward direction, it being normally in a retracted position which will permit descent of the elevator 5 to bring the matrix line in front of the mold, after which the mold wheel moves forwardly and brings

the mold into casting position with the front face of the mold in contact with the matrix line to form a metal-tight seal or lock-up therewith.

5 The mold shown in the present instance is of the recessed type shown in U. S. Letters Patent No. 1,210,078 granted December 26, 1916 to J. Keenan, the mold cap being formed on its under side with grooves or recesses 10 12 which extend in a forward and rearward direction and constitute part of the mold cavity, and the mold cap is secured rigidly or immovably to the mold body 2 by screws or equivalent fastening means 14, molds of 15 this class being adapted to cast type bars or slugs having vertical ribs projecting from one side thereof.

According to the present invention, the front lip of the mold cap, which is usually 20 employed to lock up squarely against the rear face of the matrix line, is bevelled or ground off angularly at its upper corner throughout its entire length, forming an upwardly and rearwardly inclined or angular 25 surface 15, and the lower rear corner or edge of the rear elevator jaw 8 is correspondingly bevelled or ground off to form an upwardly and rearwardly inclined or angular surface 16 which is parallel with the bevelled 30 or angular surface 15 on the mold cap. The beveling of the mold cap may be carried to any suitable depth and its angle of inclination may vary, but the bevelled surface 16 on the rear elevator jaw is always made 35 parallel to the bevelled surface 15 so that it will contact evenly and form a metal-tight joint therewith.

Such beveling of the lip of the mold cap 40 enables the rear elevator jaw 8 to descend sufficiently to reduce the height of the forward end of the mold cavity to correspond with the point size of the upper or lower character m or m' of the usual two-letter matrix, and the bevelled surface 16 of this elevator 45 jaw is in a position to contact with the bevelled surface 15 on the mold cap and thereby seal or close the forward ends of the grooves or recesses 12 in the mold cap where they are exposed by the bevelled surface 15.

50 Since the unbevelled portion of the front lip of the mold cap locks up against the rear face of the matrix line, the forward ends of the grooves 12 will be sealed from one another along this lip by the matrix line, and since 55 the normal clearance between the rear face of the matrix line and the rear jaw 8 of the elevator is usually very small and the rear jaw in the usual construction of machines of this class is sufficiently flexible to yield for- 60 wardly to bring the lowermost edge thereof into engagement with the rear face of the matrix line between or above the character punchings therein, under the pressure exerted thereon by the usual advance of the metal pot mouthpiece and mold to effect the lock-

up, and which pressure is transmitted to the rear jaw 8 by the engagement of the bevelled surface 15 on the mold cap with the bevelled surface 16 on said jaw, a metal tight seal is formed for the grooves 12 which will prevent a squirt of molten metal between the jaw 8 and the line of matrices.

70 In the operation of a line casting machine constructed as hereinbefore described, the matrix line is presented in front of the mold in the usual manner by descent of the first elevator, the jaws 7 and 8 thereof holding the matrix line in alinement with the casting cavity 11 of the mold and with the characters of the matrices from which the cast is to be made alined as usual on a level with the bottom or base of the mold cavity. When the mold wheel advances to lock the mold against the matrix line, the bevelled or angular faces 15 and 16 on the mold cap and rear elevator jaw respectively will come into contact with one another and will form a molten metal-tight joint or seal which will close off the flow of molten metal between these bevelled surfaces, and the forward pressure exerted on these surfaces by the lock-up will force the lowermost edge of the rear jaw 8 forwardly against the portion of the rear face of the matrix line above the characters alined with the mold cavity to seal or close off the flow of molten metal from the grooves 12 between the jaw 8 and the line of matrices to those portions of the matrices which are above the character against which the cast is to be made, and the forward ends of the grooves or recesses 12 in the mold cap will be thereby effectively sealed or closed to prevent leakage of molten metal therefrom. In the usual operation of line casting machines of 85 this class, the matrix line, after being lowered to position in front of the mold, is justified by the driving up of the space bands S by the justifying bar 9 and the first elevator which contains the matrix line is lifted slightly for the purpose of drawing the bottom lugs 90 m^2 of the matrices against the upper edge of the alining groove 2^a in the mold body or base, thereby producing accurate alinement of the matrices relatively to the mold, but notwithstanding the rise of the elevator during justification, an effective metal tight seal will be 100 produced between the bevelled surfaces 15 and 16 since the advance of the metal pot mouthpiece 10 against the back of the mold will drive the mold wheel 1 and the mold thereon forwardly and will effectively close any slight gap that may be produced between the bevelled surfaces 15 and 16 by the slight vertical rise of the elevator, the bevelled or inclined 110 relation of the surfaces 15 and 16 to the horizontal line of movement of the mold when moving into position to form a lock-up with the matrix line compensating for such variations as might exist in the vertical position 120 130

of the rear elevator jaw 8 relatively to the mold.

Type bars or slugs cast in a mold having a portion of its casting cavity sealed or closed in the manner hereinbefore described will comprise a relatively thin body portion 17 the thickness of which corresponds substantially with the point size of the printing characters 18 which are formed along an edge thereof and ribs 19 which project laterally from one side of the body 17 and extend in parallelism from the bottom toward the top of the slug, the upper ends of these ribs however being bevelled or inclined as at 20 so that they recede or extend downwardly and outwardly from the printing face or edge 18 and they therefore will not catch ink and smudge the printing surface during printing from such slugs, although the ribs of each slug will engage the flat sides of the adjacent slugs when the slugs are assembled in a printing form and will thereby space the printing surfaces of the slugs more widely than is usual with the standard slugs without requiring the interposing of "leads" or blank slugs between the printing slugs.

It will be understood that recessed mold caps of different point sizes may be used to cast slugs of different thicknesses, it being only necessary that the lips of the caps be bevelled at an angle corresponding with the bevelled surface 16 on the rear elevator jaw, the engagement of this bevelled surface on the rear elevator jaw by the correspondingly bevelled surface on the mold cap insuring a metal-tight seal between the matrices, rear elevator jaw and the mold cap. Since the bevelled surface 15 on the mold cap is above the liners 4 which space the cap from the mold body, the liners, according to the present invention, do not engage the rear elevator jaw and bevelling or other special shaping of the liners is unnecessary so that the usual or standard liners may be used.

The present invention enables type bars or slugs having a body portion of greater thickness than the point size of the printing characters thereon to be cast perfectly in line casting machines of the kind generally used for the casting of the standard slugs, thus making it possible to rapidly produce slugs capable of printing with widely spaced lines without the labor and expense of manually inserting "leads" between standard slugs as heretofore practiced. It enables slugs having spacing ribs with bevelled upper ends which slope away from the printing edge and which will avoid catching ink to be produced without the expense and complication of mounting the mold cap movably to permit ejection of the slug from the mold, since the bevelling of the lip of the mold cap and the sealing of the forward ends of the grooves or recesses in the cap by the correspondingly bevelled surface on the rear elevation jaw

enables the slug to be ejected forwardly from the mold by the usual slug ejecting means in the machine operating in the usual manner while the cap remains in fixed relation to the mold body, notwithstanding that the printing edge of the slug is of a thickness which corresponds only to the point size of the printing characters thereon. Owing to the close fit or tight seal formed between the mold cap and the rear elevator jaw, no leakage of molten metal, which might produce projecting fins on the slugs, can occur, these bevelled surfaces accommodating themselves to variations in the relative positions of the mold cap and rear elevator jaw and, hence, always producing a metal-tight lock-up.

Type bars or slugs produced by the casting means provided by the present invention are of the same general class as those disclosed in U. S. Letters Patent No. 1,742,981 granted Jan. 7, 1930 to L. W. Willis and are capable of being used for the same purposes, but possess the advantage thereover of greater lightness in weight since less type metal is required in forming the spacing ribs.

I claim as my invention:—

1. In a line casting machine, the combination of a mold having a cavity therein for casting a type slug and embodying a cap having a bevelled surface through which a portion of the mold cavity is exposed, and a member for bringing a matrix line into position in front of the mold, said member having a bevelled surface thereon cooperative with the bevelled surface on the mold cap to seal said exposed portion of the mold cavity.

2. In a line casting machine, the combination of a matrix line holding member and a slug casting mold movable toward said member to bring a face of the mold against the matrix line, the mold having a surface through which a portion of the mold cavity is exposed and which is bevelled relatively to the plane of the matrix-engaging face of the mold, and the matrix line holding member having a surface which is bevelled to correspond with said bevelled surface on the mold and engageable therewith to close the portion of the mold cavity exposed therethrough.

3. In a line casting machine, the combination of a matrix line holding member and a slug casting mold movable toward said member to bring a face of the mold into engagement with a matrix line held by said member, the mold having a bevelled surface adjacent to its matrix engaging face through which a portion of the mold cavity is exposed and which lies in a plane at an incline to the direction of movement of the mold toward the matrix line, and the matrix holding member having a bevelled surface opposed to and cooperative with said bevelled surface on the mold to close the portion of the mold cavity exposed therethrough.

4. In a line casting machine, the combination of a vertically movable elevator having jaws for supporting a matrix line, and a laterally movable slug casting mold having a face engageable with a side of the matrix line, the mold having a bevelled surface which is inclined to the matrix engaging face of the mold and to the direction of movement of the latter and exposes a portion of the mold cavity, and one of the jaws of the elevator having a correspondingly bevelled surface cooperative with that of the mold to close said exposed portion of the mold cavity.
5. In a line casting machine, the combination of a vertically movable elevator having jaws for holding a matrix line, and a slug casting mold having a face movable laterally into engagement with a side of the matrix line below one of said jaws, the mold embodying a recessed cap having a lip adjacent to the matrix engaging face bevelled at an incline to said matrix engaging face and exposing the ends of the recesses in the mold cap, and one of the jaws of the elevator being bevelled to correspond and cooperate with the bevelled lip of the mold cap to close the exposed ends of the recesses therein.
6. In a line casting machine, the combination of a vertically movable elevator having jaws for holding two-letter matrices, and a laterally movable mold having a face engageable with a side of the matrix line and having a slug casting cavity therein of a point size larger than that of the letters of the matrices with which it cooperates, one of the jaws of the elevator having a portion extended over the mold engaging face of the matrix line to confine the area exposed to the mold to the point size of the matrix character and having the side thereof toward the mold bevelled to extend at an incline to the mold engaging face of the matrix line, and the mold having a correspondingly bevelled surface which exposes a portion of the mold cavity and is engageable by said bevelled portion of the elevator jaw to close said exposed portion of the mold cavity.

In testimony whereof I have hereunto set my hand.
